(57) **CLAIM**

The ornamental design for a getter plate, as shown and described.

DESCRIPTION

FIG. 1 is a perspective view of a getter plate in accordance with a first embodiment of the design;

FIG. 2 is a front view thereof;

FIG. 3 is a back view thereof;

FIG. 4 is a right side view thereof;

FIG. 5 is a left side view thereof;

FIG. 6 is a top view thereof; and

FIG. 7 is a bottom view thereof.

FIG. 8 is a perspective view of a getter plate in accordance with a second embodiment of the design;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.

The broken lines shown in the figures that are immediately adjacent to the shaded areas and define unshaded regions represent the bounds of the claim and form no part of the claimed design.

1 Claim, 6 Drawing Sheets
